(57) CLAIM

The ornamental design for a bow tie with biblical phrases and musical notes, as shown and described.

DESCRIPTION

FIG. 1 is a front elevation view of the bow tie with biblical phrases and musical notes showing my new design; FIG. 2 is a rear elevation view thereof; FIG. 3 is a first side elevation view thereof; FIG. 4 is a second side elevation view thereof; FIG. 5 is a top plan view thereof; and, FIG. 6 is a bottom plan view thereof. The stars and words "LOVE" "AND" "PEACE" are colored gold as indicated by illustrated hatching patterns. Musical notes are colored black as indicated by solid black fill.
